[57] CLAIM

The ornamental design for a personal care textile article with label, as shown and described.

DESCRIPTION

FIG. 1 is a top perspective view of a personal care textile article with label shown in folded state;
FIG. 2 is a top plan view thereof;
FIG. 3 is a front, elevational view thereof;
FIG. 4 is a rear, elevational view thereof;
FIG. 5 is a right side elevational view thereof;
FIG. 6 is a left side elevational view thereof;
FIG. 7 is a top perspective view of a personal care textile article with label shown in an unfolded state;
FIG. 8 is a top plan view thereof;
FIG. 9 is a right side elevational view thereof;
FIG. 10 is a left, elevational view thereof;
FIG. 11 is a front, elevational view thereof;
FIG. 12 is a rear, elevational view thereof;
FIG. 13 is a top perspective view of a personal care textile article with label shown in an alternate folded state;
FIG. 14 is a top plan view thereof;
FIG. 15 is a rear, elevational view thereof;
FIG. 16 is a front, elevational view thereof;
FIG. 17 is a bottom plan view thereof;
FIG. 18 is a right, elevational view thereof; and,
FIG. 19 is a left, elevational view thereof.

The broken lines are shown for illustrative purposes only and form no part of the claimed design.
